UNITED STATES PATENT OFFICE.

OTTO J. KRAEMER, OF PORTLAND, OREGON.

COMBINED READING GUIDE, PAPER CUTTER, AND BOOKMARK.

Application filed November 8, 1921. Serial No. 513,856.

To all whom it may concern:

Be it known that I, OTTO J. KRAEMER, a citizen of the United States of America, and resident of Portland, in the county of

5 Multnomah, in the State of Oregon, have invented certain new and useful Combined Reading Guide, Paper Cutter, and Bookmark, of which the following is a specification, reference being had to the accompanying drawing.

10 My invention relates to improvements in desk implements which may be made of a single piece of sheet material, and has for its object the production of such a device 15 which may be used with equal facility, either for a paper cutter or for a book mark, and which is also available for a guide to the eye, to relieve it from strain, in reading, and particularly the reading of fine print or of 20 tabulated written or printed matter, particularly that which necessitates the following by the eye of a line broken by interspersed blanks or spacings.

25 What constitutes my invention will be hereinafter specified in detail and succinctly set forth in the appended claims.

In the accompanying drawing,

30 Figure I is an edge view of a closed book, partially broken away, showing my device 35 inserted, as a book mark, between two leaves thereof.

Figure II is a top plan view of my device.

Figure III is a bottom plan view of the same, or a view of the reverse side from that 35 shown in Figure II.

Referring to the numerals on the drawing, 1 indicates a handle, 2 a stop or thumb-piece projecting from its surface at one end thereof, and 3 a head provided with a straight- 40 edge 4, disposed, preferably, at right angles to the longitudinal axis of the handle 1.

The said head is preferably of a generally triangular contour, being defined by its forward edge 4, and by lateral cutting edges 45 5 that are convergent and are merged into the lateral edges of the handle 1.

The straight-edge 4 is preferably bevelled on one side, as indicated at 6, and provided, likewise, with a graduated measuring scale 50 7 inscribed upon its reverse side, or that side which is opposite to that from which the stop or thumb-piece 2 projects.

The edges 5 are oppositely disposed towards each other at such angles, respectively, 55 to the longitudinal axis of the handle as are

suited to render them conveniently serviceable for cutting the unsevered leaves of a book or the like.

My device may be made, as already specified, of any suitable material in sheet form, 60 For example, it may be made of composition like opaque celluloid, or of any suitable metal. For ordinary purposes, a cheap metal may be used in its manufacture; but it may be made attractive as a souvenir by 65 making it of silver or gold and in any preferred ornamental design that may lend durability and permanence of value to it.

In use, my device is designed to be manipulated by the thumb-piece 2 held between the 70 thumb and finger, or, being reversed, it may be slidably supported for manipulation on an incline by the member 2 and the forward edge 4 of the head 3, against a written or printed page. By either of said methods of 75 manipulation, the edge 4 is in operation adjusted to the line of matter to be read, and afterwards, in like manner, moved, line by line, as the reading progresses.

The provision of graduations to constitute 80 the scale 7, and of the lateral edges 5, as well as of the projecting member 2, all in combination with its reading-guide function, contributes to extend the range of usefulness of the device as a desk implement. 85

What I claim is:

1. In a device of the kind specified, the combination with a handle, of a straight-edge in the same plane with the handle and disposed substantially at right angles to the 90 longitudinal axis of the handle, and a member projecting from the surface of the handle, substantially at right angles thereto, to constitute a thumb-piece or stop.

2. In a device made as specified, of a 95 single sheet of material, the combination with a handle, and a member projecting from the surface thereof, at one end thereof, of a head on the opposite end thereof defined by a straight-edge substantially at right 100 angles to the longitudinal axis of the handle, and by lateral cutting edges.

In testimony whereof, I have hereunto set my hand in the presence of two subscribing witnesses.

OTTO J. KRAEMER.

Witnesses:

JOHN B. CLELAND,
JOSEPH L. ATKINS.
